SAFETY RAZOR

Leon A. Flinker, Detroit, Mich., assignor of one-fourth to John A. Geismar, Toledo, Ohio

Application January 12, 1931, Serial No. 508,164
Renewed August 10, 1934

15 Claims. (Cl. 30—12)

This invention relates to safety razors, and more particularly to a self-sharpening razor.

An object of the invention resides in the provision of a sharpening surface adapted to be fixedly positioned when in operating position and means permitting the blade to be reciprocated over the sharpening surface and to hold the blade at a fixed angle relative to said sharpening surface during the sharpening action.

10 A further feature resides in means for slidably supporting the blade whereby it moves parallel with the surface of the sharpening device and means for universally supporting the blade whereby it may be turned over at will and sharpened on either side.

15 Other features of the invention reside in the novel structure for supporting and placing the blade in two distinct positions; namely, sharpening position and shaving position, together with means for locking the blade and its supporting structure in either of said two positions.

20 Other features of the invention reside in means for relatively reciprocating the guard plate and sharpening device, the guard plate being lowered by the same action which releases the razor from shaving position, the continuing of this action raising the sharpening device to the correct plane and locking the 25 guard plate and sharpening device in sharpening position.

25 Still further features reside in resilient means for automatically moving the razor support to sharpening position and resilient means for holding the razor support in backed-away position and similar resilient means for holding the 30 razor in shaving position.

Other features and advantages therefrom will 35 be more clearly set forth in the specification and claims.

In the drawings:

Fig. 1 is an enlarged side elevation of a razor constructed in accordance with the present invention and showing the razor support and razor in position for sharpening, the guard plate having been lowered and the sharpening device raised.

Fig. 2 is a front view of the structure shown in Fig. 1.

50 Fig. 3 is a bottom plan view of the handle. Fig. 4 is a fragmentary view similar to Fig. 1, but showing the razor and its supporting structure pushed forward to approximately the end of the forward sharpening position.

55 Fig. 5 illustrates the step of swinging the

razor back and moving of the support to its forward locked position.

Fig. 6 is similar to Fig. 5 but shows the razor moved forward to shaving position.

Fig. 7 is a view taken on line 7—7 of Fig. 6.

Fig. 8 is a plan view of the razor shown in Fig. 1, but with the razor blade swung back to open position, the dotted lines illustrating the manner of turning the razor around.

Fig. 9 is a longitudinal sectional view taken 10 through the razor handle.

Fig. 10 is a view similar to Fig. 9 but showing the razor locked in shaving position with the guard plate raised and the sharpening device locked.

Fig. 11 is a sectional view taken on line 11—11 of Fig. 10.

Fig. 12 is a sectional view of the reciprocable plunger as taken on line 12—12 of Fig. 10.

Fig. 13 is a plan view of one form of razor 20 and razor holder.

Fig. 14 is a view taken on line 14—14 of Fig. 13 showing the overlapping of the blade holder to secure the blade in place.

Fig. 15 is a view taken on line 15—15 of Fig. 25 13 and showing the positioning of the blade by the blade holder.

Fig. 16 is an end view of the razor blade and holder shown in Fig. 13.

Fig. 17 is a view similar to Fig. 16 but showing the razor blade and holder formed of a single piece.

Fig. 18 is a fragmentary detail view of the means for slidably supporting the razor.

Fig. 19 is a view similar to Fig. 18 but showing the support moved forward into shaving position.

Fig. 20 is a fragmentary sectional view taken on line 20—20 of Fig. 19.

The self-sharpening razor as embodied in the drawings may be classed with that type of razor wherein the blade is sharpened or honed without removing it from the razor, as contrasted with those razors in which the blade is adapted to be stropped; in other words, I have provided a razor which may be operated to sharpen the edge of the blade by subjecting it to an abrasive or grinding action both against and with the surfaces forming the edge of the blade.

My razor, as embodied in the drawings, comprises a hollow handle 1 which is preferably rectangular in cross-section. The upper end of this hollow handle is adapted to receive a reciprocable plunger 2 and a U-shaped outer sleeve 3. The back of the plunger 2 is preferably folded 55

over to form a double wall as at 4 and this double wall is apertured at 5 to receive the end 6 of a double action toggle member 7. The other end 8 of this toggle member protrudes through an opening 9 in the face of the sleeve 3, as best shown in Fig. 2. As the toggle member 7 is pivotally mounted in the handle by means of the shaft 10, it will be obvious that movement of the sleeve 3 in one direction will be accompanied by a similar movement of the plunger member 2 in the opposite direction.

The upper end of the sleeve 3 terminates in a guard plate 11, which preferably has a smooth surface 12 for contacting evenly with the under side of the blade, as shown in Figs. 6 and 10, and suitable teeth 13 offset downwardly from the surface 12 to provide a recess for receiving soap and hair; such soap and hair thus collecting in between and under the teeth and away from the razor blade. The upper end of the plunger 2 is fabricated to provide a cage for receiving a sharpening device 14. The ends of the cage are preferably provided with stops 15 for engaging suitable members formed on the edge of the razor blade, as best shown in Fig. 4, for limiting the forward movement of the sharpening stroke. A spring member 16 of novel formation has a U-shaped portion protruding within suitable apertures formed on each side of the hone or sharpening device 14 engages with one wall of the cage whereby to hold the same in position.

The hone or sharpening device 14 preferably has a flat upper surface for uniform contact with the edge of the razor blade. This hone may be formed of various kinds of material and I have found that exceptionally good results may be obtained by forming the same of nickel. This nickel or any other material which would be relatively porous presents a very fine sharpening surface as rouge or other abrasive material may be rubbed on the porous surface and absorbed by the pores so as to present a very fine sharpening surface which need not be wiped or washed off each time the razor is used. In other words, where abrasive material, in addition to the material of the hone, is used, it is retained by the pores of the hone itself. The upper surface of the hone may be fabricated or cut so as to present fine diagonal corrugations or ridges 17 which, if used, are preferably relatively fine on one side and relatively coarse on the other side, the finer ones producing a finer razor edge for certain types of beards. In addition to producing a fine edge very quickly they help materially in retaining the sharpening composition in place on the hone.

The lower end of the sleeve 3 is provided with an aperture 18 and spaced below this aperture is a hook member or catch 19. A long integral spring 20 enters the back side of the handle 1 and preferably extends to the bottom of the handle, as best shown in Fig. 1, and then upwardly to a point adjacent the lower end of the sleeve 3. The front wall of the handle 1 is provided with an aperture 21 and the one end of the spring 20 is bent over as at 22 to form a locking member which is in constant registration with the aperture 21.

A release finger 23 is pivotally mounted on the sleeve 3, as best shown in Fig. 11, and the handle 1 is slotted as at 24 to permit up and down movement of the finger 23 and the sleeve 3. A contact member 25 is secured to the spring 20 and protrudes through the front wall of the

handle 1 for contact with the member 23. It will be obvious that inward movement of this pivoted releasing finger 23 will contact with the member 25 and move the spring member, and the bent over portion 22 thereof, inwardly. The downward position of the sleeve member 3 is such that the aperture 18 registers with the aperture 21 of the handle whereby the member 22 is adapted to hold the sleeve 3 in locked downward position. Likewise, the upward position of the sleeve 3, see Fig. 10, results in registration between the member 19 and the aperture 21 with the result that a release of the finger 23 permits the member 22 of the spring to engage with this catch 19 to lock the sleeve in shaving position, as shown in Fig. 10.

The razor, instead of being directly supported by the handle, is carried by a supporting unit which may be generally designated 30. This support preferably consists of an arm 31 extending at right angles to the axis of the handle and an angularly extending arm 32 terminating in a pivot 33, which pivot serves as a connecting means with a second arm 34 which directly receives and supports the razor 35 and its holder 36.

The handle 1 is apertured as at 31a, see Fig. 9, to guide and support the arm 31. This arm 31 is provided with an aperture 38 and the front wall of the sleeve 3 is provided with an aperture 39, the latter aperture permitting reciprocatory movement of the lever 31 and the aperture 38 permitting reciprocatory movement of the sleeve 3. In other words, in the position shown in Fig. 10, which is the shaving position, the arm 31 is moved forward to a position where the sleeve 3 is passed upwardly through the aperture 38. It will be obvious that in this position the entire supporting unit 30 is locked in its forward position.

Now, if the sleeve member 3 is moved downwardly, it will be obvious that the arm 31 will be released. The rear end of the arm 31 is apertured to receive the upper end of the spring 30 so that with release of the lever 31 by downward movement of the sleeve 3 the spring 20 will automatically tend to move the entire supporting unit 30 to the position shown in Fig. 1.

The arm 34 is provided with an aperture 40 which is adapted to cooperate with the spring 16 when the entire supporting unit 30 is moved to shaving position, such as that shown in Fig. 10. The upturned end of the spring 16 thus serves as an additional lock to keep the razor blade in shaving position. While the locking of the arm 31, of course, positively locks the entire supporting unit 30, if it were not for the spring 16 the pivot 33 might permit the blade to rise up when contacting with the face. The spring 16 thus insures that the blade 35 will remain in contact with the guard plate during shaving operation. In order to disengage the spring 16 and permit the razor blade supporting unit to be moved to sharpening position, the arm 34 must be first pivoted about the pivot 33, as shown in Fig. 5.

Now, in order to keep the arm 34 in this position I have provided a spring member 41 which is adapted to engage an aperture 42 in the upstanding arm 32, as best shown in Fig. 5. It will thus be obvious that either the spring 16 or the spring 41 is in operating engaged position as the arm 34 and the razor blade is always either in the position shown in Fig. 5 or that shown in Figs. 4 and 10. It will also be seen from Fig. 8 that the pivot 33 is provided with

a suitable coil spring which tends to hold the razor blade against either the hone or the guard plate.

The arm 34 is provided with a lateral extension 43 with the result that either the forefinger or the thumb, depending upon the way the razor is held, may be conveniently rested against the extension 43 and the arm 34 to either move the razor blade and its holder to the position shown in Fig. 5 or to return the same to the position shown in either Figs. 1 or 10.

The razor blade holder 36 may be of any convenient form such as that shown in Figs. 15 and 16 or may be solid as shown in Fig. 17. As best shown in Fig. 10, such holder may be secured to the arm 34 by means of a suitable screw 44.

The distance that the arm 31 is retracted when released is very important and in order to insure such correct distance, I have provided a downwardly extending portion 45 on the end of the arm 31, the operation of which can be readily seen in Figs. 9 and 10. The outward position of the arm 31, which is that shown in Figs. 1 and 8, permits the blade 35 and holder 36 to be swung arcund due to the swivel joint 44, such as indicated in dotted lines in Fig. 8. In other words, it is only necessary when the razor is in honing position such as shown in Fig. 1, to retract the arm 34 until the spring 41 engages in the aperture 42, when the blade and holder can be freely moved around to present either side to be sharpened.

Fig. 18, 19 and 20 illustrate a modified form of guide for the arm 31 in that a sleeve 46 is positioned in the handle, the under side of the sleeve being cut away as at 47 to permit the arm 31 to be retracted a greater distance with the result that, if desired, the front end of the arm 31, when in shaving position, need not extend out so far as in the preferred construction, such as shown in Figs. 6 and 7.

The wings 37 on the holder 36 are of a predetermined width so that when the razor is in shaving position, such as shown in Fig. 6, the edge of one wing 37 may be rested against the face so as to insure the correct angle in shaving. The casing for the sharpening device is preferably provided with rearwardly extending portions 50 which are so spaced as to insure that the blade always strikes the sharpening surface when the arm 34 is snapped forward. Thus, if the blade should not happen to be turned all the way around by the operator it would still not be possible to hit the edge of the blade against any part of the razor.

The back portion of the cage is cut away as at 51 and the flat surfaces 52 are adapted to contact with the inner surface of the arm 34 when the razor blade is in shaving position whereby to help square the edge of the blade with the front of the guard plate. Due to the novel arrangement of the various parts making up my razor, and including the flat sharpening surface, the manner of mounting the blade and its holder and the reciprocation of the blade at a definite angle across the sharpening surface, I am able to obtain and maintain a relatively small angle between the blade and the sharpening surface, as will be seen in Figs. 1 and 4. This angle between the blade and sharpening surface is preferably about 15° and should not be greater than 23°. It will also be seen that the angle between the surface of the blade and the edge 37 of the wing, which is the correct

angle between the blade and the face when shaving, is substantially equal to the sharpening angle. Whether this small angle is conducive to better sharpening or better shaving is not quite certain, but I have found in practice that much better results are obtained if the sharpening angle is kept below 23° and still better results are obtained if the shaving angle is likewise kept below 23°. It will be understood that the hone 14 is removable or reversible to permit easy replacement or to present a new sharpening surface.

In operation, the razor is normally in the position shown in Fig. 10. If it is desired to hone the blade the finger or thumb is placed on the extension 43 and the blade holder moved to the position shown in Fig. 5. This movement is necessary to release the lever 34 from the spring 16. With the razor retracted to this position, the finger 23 may be pressed inwardly to release the catch 22 and the outer sleeve 3 moved downwardly as best illustrated in Fig. 9. This action results in lowering of the guard plate 11 and raising of the sharpening surface 14. With the thumb or finger the razor blade can then be readily snapped to the position shown in Fig. 1 and a slight pressure on the lever 32 will cause the razor blade to be moved forwardly and backwardly over the sharpening surface as will be seen by comparing Figs. 1 and 4. Having given the blade four or five sharpening strokes, the lever 34 may be moved about its pivot 43 until the spring 41 catches when the blade may be reversed as indicated in Fig. 8 and the reverse side sharpened.

To assemble the parts in shaving position it is necessary to first revolve the razor blade and arm 34 about the pivot 33 to the relative position shown in Fig. 5, after which the arm 33 is moved forwardly to the position shown in Fig. 5. The finger 23 is again pressed inwardly and the sleeve 3 moved upwardly so that it engages and locks the arm 31 and the guard plate is raised to its normal position as shown in Figs. 5 and 10. The razor blade holder and arm 34 may then be moved forwardly so that the razor blade contacts with the surface 12 of the guard plate and the spring 16 engages and locks the razor blade in shaving position.

The intended meaning of the words "float" or "floating" as used in the specification and claims is that the blade is allowed to move in any direction or is unrestrained as it moves over the surface of the sharpening device; in other words, the blade automatically accommodates itself to the surface of the sharpening device.

What I claim is:

1. A self-sharpening razor comprising a handle, a sharpening device fixedly supported by the handle in sharpening position, a guard plate, a pivotally mounted blade, means for reciprocating the blade over the surface of said device at a fixed angle, and means for moving said guard plate below the sharpening surface of said device.

2. A self-sharpening razor comprising a handle, a sharpening device fixedly supported by the handle in sharpening position, a guard plate, a blade pivotally mounted on a blade mounting, and means for reciprocating the blade over the surface of said device at a fixed angle, said blade mounting being slidably mounted in said handle and movable bodily transversely of the

handle and parallel to the plane of movement of the blade edge.

3. A self-sharpening razor comprising a handle, a sharpening device fixedly supported by the handle in sharpening position, a guard plate, means for reciprocating the blade over the surface of said device at a fixed angle, a blade mounting slidably mounted in said handle and movable bodily transversely of the handle and 5 parallel to the plane of movement of the blade edge from sharpening position to shaving position, and means directly engaging the blade mounting for resiliently locking said blade in 10 shaving position on the handle.
4. A self-sharpening razor comprising a handle, a sharpening device fixedly supported by the handle in sharpening position, a guard plate, means for reciprocating the blade over the surface of said device at a fixed angle, a blade 15 mounting slidably mounted in said handle and bodily movable during sharpening action and transversely movable to sharpening position or shaving position, and means directly engaging the blade mounting for locking said blade in 20 shaving position.
5. A self-sharpening razor comprising a handle, a sharpening device carried by and fixedly positioned on the handle, a guard plate for receiving the razor blade in shaving position, and 25 means mounted at the back of the handle and movable bodily relative to the handle for supporting said blade in a position to be reciprocated in a straight plane over the surface of the stationary sharpening device.
6. A self-sharpening razor comprising a handle, a flat surfaced sharpening device fixedly positioned on the handle, a guard plate for receiving the razor blade in shaving position, and means mounted at the back of the handle and 30 movable bodily relative to the handle for supporting said blade in a position to be reciprocated over the surface of the sharpening device, and means for guiding the blade support to maintain the sharpening angle between the reciprocating blade and stationary sharpening device.
7. A self-sharpening razor comprising a handle, a sharpening device stationarily mounted on the handle during the sharpening operation, a guard plate for receiving the razor blade in 35 shaving position said plate and device being relatively movable, means mounted at the back of the handle and movable bodily relative to the handle for supporting said blade in a position to be reciprocated over the surface of the sharpening device, and means for automatically moving said blade supporting means into sharpening position.
8. A self-sharpening razor comprising a handle, a sharpening device stationarily mounted on said handle during the sharpening operation, a blade support slidably carried by and bodily movable transversely of said handle during the sharpening action and including a universal 40 mounting for permitting the blade to be turned over, and resilient means for locking the support in shaving position and automatically moving the support to sharpening position.
9. A self-sharpening razor comprising a

handle, a flat surfaced sharpening device stationarily mounted on said handle during the sharpening operation, and a blade support slidably mounted on and movable transversely of said handle and including a universal mounting for permitting the blade to be turned over and to float while being sharpened, said handle guiding said support during said sliding and transverse movement.

10. A self-sharpening razor comprising a handle, a flat surfaced sharpening device stationarily mounted on said handle during the sharpening operation, a blade support slidably mounted on and movable transversely of said handle and including a universal mounting for permitting the blade to be turned over and to float while being sharpened, a guard plate, means cooperating with said support for locking the same in shaving position, and means cooperating with said universal mounting for holding the blade against said plate.

11. A self-sharpening razor comprising a handle, a flat surfaced sharpening device stationarily mounted on said handle during the sharpening operation, a blade support slidably mounted in said handle to permit bodily movement of said support relative to said handle and including a universal mounting for permitting the blade to be turned over and to float while being sharpened, and slideable means on said handle cooperating with said support for locking the same in shaving position.

12. A self-sharpening razor comprising a handle, a blade and support therefor bodily movable relative to the handle, a fixedly positioned flat surfaced sharpening device, and means for guiding said bodily movable support to hold the blade at a fixed angle relative to the surface of said device while being moved back and forth across said surface.

13. A self-sharpening razor comprising a blade, a fixedly positioned flat surfaced sharpening device carried by the razor handle, a blade holder slidably carried by the handle and bodily movable relative to the handle during sharpening action, means for holding the blade at a fixed angle relative to the surface of said device while being moved back and forth across said surface, and means for resiliently and automatically moving the razor blade in one direction.

14. A self-sharpening razor comprising a blade, a flat surfaced sharpening device fixedly positioned in the razor handle during sharpening operation, and a blade support slidably and reciprocably mounted in the razor handle to permit parallel bodily movement of the support relative to the handle and surface of the sharpening device to hold the blade at a fixed angle during the reciprocating sharpening movement.

15. A self-sharpening razor comprising a handle, a flat surfaced fixedly positioned sharpening device carried by the razor handle, a blade support bodily movable relative to the handle during sharpening action and means for guiding the support to hold the blade at a fixed angle of less than 23° relative to the surface of said sharpening device.

LEON A. FLINKER.
